CHECK OR COIN SELECTOR

Frank K. Maitland, Chicago, Ill.

Application September 26, 1936, Serial No. 102,690

3 Claims. (Cl. 194—1)

This invention relates to coin control devices and has for one of its important objects the provision of novel selector mechanism for use with coin controlled vending or amusement devices.

The selector mechanism of the present invention is especially suited for use with devices including some form of cyclically operable mechanism, the selector mechanism being periodically operable to separate one or more coins from the bulk of those deposited in the coin control slide, and direct such separated coins into a special container.

Other principal objects and novel features of construction and invention will appear as the following description proceeds in view of the drawing, in which:

Fig. 1 is a vertical sectional view of an amusement device, including the selector mechanism, viewed from the side;

Fig. 2 is a rear vertical section, taken along lines 2—2 of Fig. 1; while

Fig. 3 is an enlarged operating detail of part of the selector control mechanism, the view being taken in the direction of the arrows 3—3 of Fig. 2.

The novel selector apparatus is illustrated in Fig. 1 as installed in the cabinet of an amusement device which includes a front wall 10, and a coin slide mechanism including a reciprocable slide member 12 mounted thereon.

Interiorly of the cabinet is a substantially vertical coin chute 14 having its lowermost open end overlying an aperture 16 in a horizontally extended shelf-board 18, and having its uppermost open extremity 20 underlying the rearward portion of the coin slide 12, in such manner as to receive coins deposited from the latter and direct them for gravitational movement downwardly through the aperture 16.

The shelf-board 18 has a member 22 on the underside thereof, in which are grooves for the reception of runners 24 on the sides of a pair of coin receiving drawers 26 and 28, respectively, the drawer 26 being positioned with its open upper end immediately underlying the lowermost open end 16 of the coin chute 14.

The coin receptacle or drawer 28 underlies an aperture 17 in the shelf member 18, which aperture communicates with the lowermost open extremity 30 of an inclined coin chute which communicates at its upper extremity 32 with the vertical coin chute 14, the inclined chute being a branch of the vertical chute.

The mechanism to be operated in the amusement or vending machine by deposit of a coin in

the slide 12 and manipulation of the latter, may be any one of several well known types, it being deemed sufficient for purposes of present description simply to show an operating member of an amusement apparatus, such member being in the form of a shuffle panel 36, which is supported for horizontal sliding movement beneath a horizontal partition 11 of the game cabinet. The shuffle panel 36 has a depending bracket 38 which is engageable by the rearmost end 13 of the coin slide 12 when the latter is urged inwardly after deposit of a proper coin so as to set the game apparatus into operation.

The selector mechanism includes a movable baffle or gate 40 pivoted in the side walls of the chute structure as at 42 on the shaft 41, to block the opening juncture of the inclined chute with the vertical chute 14, a suitable spring member 44 being provided on the pivotal mounting 42 to normally urge the gate 40 upwardly and close the upper end 32 of the inclined chute.

The uppermost extremity 20 of the vertical coin chute is provided with an inclined apron having its lowermost extremity 21 positioned above the uppermost extremity of the gate 40 so as to deflect descending coins away from the latter when the gate is in raised or open position.

Driving mechanism for periodically closing the gate 40 includes a bracket member 50 suspended from the upper horizontal partition 11 of the cabinet, and having at its lowermost extremity a yoke-shaped portion including a pair of oppositely disposed side walls 52. Journaled in, and extended through the side walls 52 of the yoke-shaped portion, is a driven shaft 54 having affixed to its right-hand extremity a trip wheel 56, having a flange 58 with one or more tripping pins 60 extended laterally away from the surface of the flange part. At the opposite end of the shaft 54 is a ratchet wheel 62 adapted to be driven by a pawl 64, which in turn is driven by an eccentric 66 on a driven shaft 68 (Fig. 2), which shaft is adapted to be rotated periodically by any suitable game or vending mechanism included in the particular apparatus controlled by the operation of the coin slide mechanism 12. Shaft 68, for example, could be driven from a rotatable merchandise display turntable, or by a ball elevating mechanism in a game of the pin and ball type, at the termination of the elevation of a predetermined number of balls. In short, any cyclically or periodically operating means may be used to rotate the shaft 68. The ratchet 62 is prevented from retrograde movement by means of a spring urged dog 70, which is mount-

ed on the bracket member 50 immediately adjacent the ratchet.

Driving motion is transmitted from the stepping wheel 56 to the gate 40 by means of a second pawl 72 which is connected by the cotter pin 5 means shown in Fig. 2 to an offset extremity 43 of the gate shaft 41, and at its other extremity this pawl has a notched portion 74 into which the pins 60 of the stepping wheel 56 are moved 10 as the wheel rotates. The forward (right-hand) marginal extremities of the pin slot 74 are suitably disposed (for example normally) so that the pawl 72 will be urged forwardly, from left to right, as a pin 60 is rotated through a portion 15 of its arc of travel, the pin thereafter passing out of the slot 74.

The pawl 72 preferably has a flat surface adapted to bear against the surface of the flange 58 of stepping wheel 56, and the outermost or 20 right-hand wall portion 52 of the yoke part of the bracket 50 has an offset, slotted portion 53, the slotted part of which embraces the pawl 72 so as to prevent the latter from moving out of operative engagement with the wheel 56.

25

Operation

The foregoing selector mechanism operates in the following manner. Assuming that a proper coin is deposited in the slide 12 and the latter is urged inwardly so as to cause its rearward end 13 to bear against the bracket 38 of the assumed shuffle panel 36 so as to release a game apparatus, for example, for operation, the coin deposited will descend into the vertical chute 14 at its uppermost end 29 and possibly striking the apron 21 further descend into the chute through the lowermost opening 16 and into the drawer 26 therebelow, which may be the proprietor's coin receptacle.

40 Thereafter it may be assumed that the game or vending mechanism operates through one cycle, rotating the shaft 68, (Fig. 2), and upon one complete revolution of the latter driving the pawl 64 to rotate the ratchet wheel 62 a short 45 distance and correspondingly rotating the stepping wheel 56, so that after a predetermined number of revolutions of the latter one of the pins 60 will be positioned in the slot 74 in pawl 72, and thereafter the next succeeding step will 50 cause the pawl 72 to be urged forwardly toward the right, thus pivoting the crank arm 43 and the shaft 41 to move the gate 40 against the tension of spring 44 into the dotted line position of Fig. 1.

With the gate 40 thus effectually blocking the 55 passage in the vertical chute 14, the next coin to be deposited in the latter from the coin slide 12 will be deflected by the gate into the descending chute through the lower opening 17, and into a coin receiving drawer or receptacle 28 which 60 may be the operator's receptacle.

In the example shown in Fig. 1, the stepping wheel 56 is provided with two pins 60 so that the gate 40 will be opened twice during each revolution, and it will be apparent that any number of 65 such pins 60 may be provided to operate the gate 40 a corresponding number of times for each cycle of operation of the wheel 56. In each instance, the gate 40 will remain in blocking position until a pin 60 moves out of the slot 74 in arm 72, the spring 44 being effective thereafter 70 to return the gate to normal position, closing the inclined chute.

While the embodiment just described in detail represents a preferred form of the invention, I do not desire to be restricted to any precise details of structure or operation other than may be provided for in the following claims which I 5 desire to protect by Letters Patent of the United States.

I claim:

1. Coin selecting means for use with apparatus having a coin deposit device adapted to free 10 a driven mechanism for operation, said means including coin guiding means positioned to receive coins from said deposit device, coin deflecting means movable from a normal position to deflect the direction of movement of coins in 15 said guiding means, together with driving mechanism for periodically moving said deflecting means from said normal position into deflecting position, said driving mechanism comprising a driving arm operatively connected with said deflecting means at one end, and having a notch 20 near an opposite end, a driven wheel having pin means engageable in said notch periodically upon rotation of said driven wheel to move said arm and the deflecting means connected therewith, a 25 ratchet member operatively connected with said driven wheel, an eccentric operable in cycles by a driving connection with the aforesaid driven mechanism, a pawl driven by said eccentric and arranged to drive said ratchet, substantially as 30 described.

2. Operating mechanism for coin operated devices having a driving mechanism and a movable coin selector, said mechanism comprising a substantially U-shaped bracket, a shaft extended 35 through the opposite sides of the bracket, a trip wheel mounted near one end of the shaft and provided with a tripping pin, a ratchet wheel near the opposite end of said shaft, means mounted on said bracket and preventing retrograde movement of said ratchet, a pawl for said ratchet, an eccentric drivingly connected with said pawl and operable by the aforesaid driving mechanism, a second pawl and operatively connected at one end to said coin selector, and having a formation near its opposite end engageable periodically by said tripping pin as said trip wheel is revolved by said ratchet.

3. Operating mechanism for coin operated devices having a driving mechanism and a reciprocably operable coin selector, said mechanism comprising a substantially U-shaped bracket, a shaft extended through opposite sides of the bracket, a trip wheel having an annular flange adjacent its periphery and a laterally extending 55 trip pin extended from said flange, a ratchet wheel at one end of said shaft, a dog on said bracket and preventing retrograde movement of said ratchet wheel, an elongated pawl drivingly engageable near one end with said ratchet wheel, 60 an eccentric driven by the aforesaid driving mechanism and drivingly connected with said pawl, and a second elongated selector pawl operatively connected with said selector near one end and having a notch formation near its opposite 65 end, means on said bracket holding said end of the second pawl with the notch formation close against said flange on the trip wheel, said trip pin periodically and transiently engaging the notched part of said pawl and moving the latter 70 to operate said selector.

FRANK K. MAITLAND.
